UNITED STATES PATENT OFFICE.

GEORGE THOMAS BUCKHAM AND JOHN IRVING NASMITH, OF WESTMINSTER, LONDON, ENGLAND, ASSIGNORS TO VICKERS LIMITED, OF WESTMINSTER, LONDON, ENGLAND.

WIRE-STITCHING MACHINE.

1,422,081.

Specification of Letters Patent.

Patented July 11, 1922.

Application filed November 3, 1921. Serial No. 512,629.

To all whom it may concern:

Be it known that we, GEORGE THOMAS BUCKHAM and JOHN IRVING NASMITH, both subjects of the King of Great Britain, residing at Wickers House, Broadway, Westminster, in county of London, England, have invented certain new and useful Improvements in or Relating to Wire-Stitching Machines, of which the following is a specification.

This invention relates to wire stitching machines and although of general application has more particular reference to machines for stitching folding cardboard boxes or the like. In wire stitching machines as at present in use the clinching operation is usually performed either by the staple legs being driven by the stapling mechanism onto a fixed plate which is so formed that it turns the staple legs inwards and so clinches the same, or else moving clinchers are employed which are located in the bed plate or anvil of the machine, the moving clinchers being operated by mechanism contained in the body of the anvil or bed plate and comprising some special attachment such as a cam or the like which co-operates with the driving mechanism of the machine. Machines of the last mentioned type possess the disadvantage that it is necessary to withdraw the box back over the anvil after the stitching operation is completed.

According to the present invention the parts of a wire stitching machine are so constructed and arranged that the staples inserted in the boxes or the like are clinched by clinching dogs carried by an anvil or clincher box in such manner that the usual mechanism located in the anvil for actuating the clinching dogs is dispensed with, thereby permitting the boxes or the like which are being stitched to be passed continuously over the anvil, thus dispensing with the necessity of having to withdraw the box back over the anvil or clincher box after the stitching operation is completed.

In order that the said invention may be clearly understood and readily carried into effect the same will now be described more fully with reference to accompanying drawings which show by way of example one embodiment of a machine constructed ac-

cording to the present invention and in which:

Figure 1 is a front elevation of the machine showing the former in its arrested position, the staples being about to be driven through the work.

Figures 2, 3 and 4 are sectional views of details, the sections being taken respectively on the lines 2-2, 3-3 and 4-4 of Figure 1, and

Figure 5 is a side elevation of Figure 1 showing part of the rocking bar which is pivotally mounted upon the arm of the machine and which carries the clinching bolt of the stapling mechanism.

A is the table or work support of the machine and B is an anvil or clincher box which is movable relatively to the table A, the movable anvil B being provided with an extension b which acts as a support for the work. C, C are the clinching dogs which are pivotally mounted by means of pins within a recess in the anvil and D is a light blade spring which is bent around one end of the anvil as shown and which bears upon the lower faces of the clinching dogs C, C and serves to retain the clinching dogs in their normal position, to protect the bottom surface k² of the box from being marked or damaged by the clinching dogs during the clinching operation and also to resist the forces set up by the penetration of the staple. E is the front plate or casing of the stapling mechanism which latter is positioned above the anvil B. The casing E contains a former F and a driver G, the former F being capable of sliding movement within the casing E while the driver G is mounted within the former F and is capable of relative sliding movement therein. The former F is provided with a laterally projecting flange or bracket f which carries an adjustable stud f' the upper end of said stud f' acting as a stop, as hereinafter explained, and the lower end thereof being adapted to bear upon a spring controlled

buffer H which is mounted within a box or casing H' attached to the casing E. The driver G is also provided with a laterally projecting bracket g the said bracket g carrying an adjustable stud g' which as hereinafter explained, acts as a clinching

bolt. The lower end of the clinching bolt g' is normally positioned (as shown) above the head of the stud f' . The buffer spring H is mounted around the stem of a bolt h' the lower end of the latter being connected to a member I which is capable of sliding movement relatively to the casing E and which acts as a guide and a presser foot for the work. The member I is bifurcated at 10 its lower end, the bifurcated parts i, i' , being located respectively on either side of an extension e of the front plate E, the parts being held in place by a securing plate e' and stud e^2 . Connected to the lower end of the 15 member I is a guide plate J forming part of the anvil B; the anvil is thus joined to the buffer H by the sliding connection which is in turn supported by the buffer spring. As more clearly shown at Figure 2, the said 20 guide plate J is provided with a downwardly inclined surface j which receives one edge k' of the box which is to be stapled and with a recessed part j' which is upwardly inclined and which receives the other edge 25 k of the box, these inclined surfaces being so arranged that as the box is passed over the anvil the edges thereof overlap one another so as to form a lap joint. The member I also carries a blade spring i which 30 bears upon the work. By attaching the anvil B to the buffer H through the intermediary of a sliding connection and also by supporting it by means of the leaf spring D, the anvil is prevented from twisting during 35 the clinching operation.

In operation, the two parts k, k' of the box which are to be stapled are passed over the two inclined surfaces j, j' so that they overlap one another, while the lower surface k^2 40 of the box rests upon the table A beneath the anvil B. In the operation of driving the staple L into the work the downward movement of the former F is arrested on reaching the surface of the box and prior to the driving 45 of the staple through the work by the lower end of the stud f' coming into contact with the spring controlled buffer H. The driver G thereupon continues its downward movement independently of the former F 50 and drives the staple L through the work, the clinching dogs C, C during the driving-in movement remaining depressed against the resistance of the leaf spring D beneath the anvil so that they present a sloping surface 55 to the legs of the staple L. The adjustment of the parts is such that when the lower surfaces of the driver G and the former F come into line or are on the same level the clinching bolt g' carried by the driver G 60 comes into contact with the head of the stud f' thereafter the driver G and the former F as also the sliding connection I with its extension J, move down simultaneously and depress the anvil B on to the table A of the 65 machine. The clinchers C, C are thereupon

pressed upwards until their upper surfaces are level with the top of the anvil B. During this movement the legs of the staple are bent inwards and clinched. The clinching operation is thereby performed independently of any other mechanism, while the leaf spring D which is positioned above the lower surface k^2 of the box protects the same from being marked or damaged. 70

What we claim and desire to secure by 75 Letters Patent of the United States is:—

1. A wire stitching machine comprising a work support, an anvil positioned above said work support and movable relatively thereto, clinching dogs mounted within said 80 anvil, stapling mechanism movable relatively to said anvil, the downward movement of said stapling mechanism being adapted to drive the staples through the work and by its continued downward movement to clinch 85 the staples by depressing the anvil on to the work support.

2. A wire stitching machine comprising a work support, stapling mechanism, an anvil or clinching box which is movable relatively 90 to the work support and within which clinching dogs are pivotally mounted, the operation of clinching the staples being performed automatically during the downward movement of the stapling mechanism, and 95 after the staples have been driven through the work by depressing the movable anvil into contact with the work support.

3. A wire stitching machine comprising 100 stapling mechanism, an anvil which carries the clinching dogs, a work support positioned beneath said anvil, said anvil being spring controlled and being movable relatively to the work support, the downward movement of said stapling mechanism being 105 adapted to drive the staples through the work and by its continued downward movement to clinch the staples by depressing the anvil on to the work support.

4. A wire stitching mechanism for folding 110 boxes comprising a work support, a movable anvil located above said work support and within which clinching dogs are pivotally mounted, the upper face of said anvil being adapted to receive the overlapping 115 edges of the boxes which are to be stitched together, the lower surface of the box being positioned beneath said anvil and resting upon said work support, a blade spring being provided beneath the clinching dogs so 120 as to protect the lower surface of the box during the clinching operation.

5. A wire stitching machine for folded 125 boxes comprising stapling mechanism, a work support, a movable anvil located above said work support and within which the clinching dogs are pivotally mounted, the upper face of said anvil being adapted to receive the overlapping edges of the boxes which are to be stitched together, the lower 130

surface of the box being positioned beneath said anvil and resting upon said work support, the stapling mechanism being adapted to drive the staples into the work by its 5 downward movement, and by its continued downward movement to clinch the staples by pressing the anvil on to the work support.

6. A wire stitching machine for folded boxes comprising stapling mechanism, a 10 work support, a movable anvil located above said work support and within which clinching dogs are pivotally mounted, the upper face of said anvil being adapted to receive the overlapping edges of the boxes which are to be stitched together, the lower surface of 15 the box being positioned beneath said anvil and resting upon said work support, a blade spring being provided beneath the clinching dogs so as to protect the lower surface of the box during the clinching operation, the 20 stapling mechanism being adapted to drive the staples into the work by its downward movement, and by its continued downward movement to clinch the staples by pressing the anvil on to the work support.

GEORGE THOMAS BUCKHAM.
JOHN IRVING NASMITH.
